UNITED STATES PATENT OFFICE

2,233,843

CONTAINER

Charles E. McClaskey, New Philadelphia, Ohio

Application October 13, 1937, Serial No. 162,758

1 Claim. (Cl. 220—58)

The present invention relates to the manufacture of receptacles or containers such as used for garbage or other waste material. The object of the invention is to construct a lid or cover for the container which is easily locked in position so that accidental displacement of the lid is prevented. The device is characterized by the feature that the lid is locked in place by rotating it on the can, and by engagement of the bail ears with a projecting flanged or beaded portion of the lid. The design and arrangement of the parts are simple and inexpensive.

Containers with locking lids have been known heretofore but the advantages of the present invention lie in the simplicity of the means employed and its efficiency and inexpensiveness as it can be made by simple stamping methods. In fact this special form of container and lid may be manufactured at a cost not exceeding the cost of manufacture of an ordinary container.

In the drawing and description, the best known and preferred form of the invention is illustrated, but it will be understood that the principles of the invention may be carried out in other specific forms and embodiments.

In the drawing:

Fig. 1 is a side elevation of the improved form of container or can in its best known or preferred embodiment;

Fig. 2 is a top plan view of the can showing the lid in locked position in full lines and in unlocked position in dotted lines;

Fig. 3 is a fragmentary view of the ear or bail attachment with the lid unlocked and in position to be raised;

Fig. 4 is a detail of a bail ear blank in its flattened condition;

Fig. 5 is a fragmentary view of a modification of the invention.

The numeral 1 indicates the body of the can or container which, as shown, is round in cross section and upon which is the lid 2 provided with the customary handle 3. The bail is indicated at 5 and is pivoted in the bail ears 6 on either side of the can.

The construction of these bail ears is particularly to be noted. The bail ears constitute lugs with which the lid will interlock when it is placed in certain angular positions on the can. In other angular positions the lid will release from the can. In the form shown in Figs. 1 to 4, the bail ear is made from a flat-stamped metal blank which is folded at the middle and provided with lugs by which it is secured to the body of the can by riveting if desired. It may be soldered or welded.

The form of the sheet metal blank before folding is shown in Fig. 4. In its finished form the ear comprises the body portion 8 in the upper corner of which is formed the hole 9 for the reception of the bail. On its upper, inner edge is provided the recess 10, preferably formed by the downwardly extending tip 11. This blank may be made from scrap metal with little loss.

The lid is provided with the usual downwardly extending rim provided with outwardly extending beaded edge or flange. The lid however is not circular, as is the usual construction, but is oval or elliptical in form with the short axis of the ellipse equal approximately to the diameter of the top of the can. When placed with the short axis of the lid, across the can, or in line, or approximately in line with the bail ears, the rim and its bead or flange will clear the overhanging portion of the ears where it lies between the body of the can and the ears, as shown in Figure 3, in which position the lid may be lifted from the can.

When rotated through approximately 90 degrees or to the position shown in Figure 1 and in full lines in Figure 2, the excess width on the long axis of the lid will throw the beaded edge into the recesses in the bail ears beneath the overhanging portions 11 and the lid cannot be lifted or knocked off the can. By the simple act of turning the lid, it may be moved to locked or unlocked position.

The principal features of the invention are the formation of the bail ears so that the rim of the lid is received between the body of the can and the inner faces of the ears and the provision of the recesses in the inner walls of the bail ears to interlock with the lid on its rotation. In the preferred form, the interlocking is secured by forming the lid in a non-circular or elliptical form so that the long axis of the lid affords the interlocking. This form is preferred as it merely necessitates an oval or elliptical die for stamping out the lid. Cutting of the lid is not required and consequently there is no waste material and no weakening of the lid.

The lid is preferably formed on a true ellipse so that an unbroken and uninterrupted bead will be retained. In cans in which the lid is cut or flattened at regions to provide for the interlock, the bead is necessarily divided and discontinuous which serves to weaken the lid and to destroy the strengthening and form retaining properties of the bead, whereas in the construction shown herein the bead is not destroyed, but is continuous and unbroken, thus preserving the full

strength of the structure while allowing for the rotating locking feature.

In the modification shown in Fig. 6, the bail ears 30 are formed with outwardly facing recesses 31 and the lid with an inturned flange 32 on the rim. The elliptical formation of the lid causes the lid and body to be interlocked on rotation of the lid, but in this case the locking of the parts occurs when the short axis of the ellipse is in alignment with the bail ears or lugs. In this form lugs stamped outwardly from the body of the can may be employed in place of the bail ears.

In all forms of the invention the lid cannot be removed except by rotation of the lid. The lid, therefore, cannot be knocked off accidentally. A reversal of the preferred form is possible, i. e., making the can body elliptical and the lid circular, but obviously the elliptical lid is preferable.

Such a variation in construction is shown in my copending application Serial No. 173,416, filed November 8, 1937.

What is claimed is:

A container having a circular body and a lid therefor having a downwardly extending flange loosely fitting around the body to allow for rotation of the lid on the body, the lid being in the form of an ellipse and having a continuous out-turned bead of uniform cross-section around the lower edge of the flange and lugs on the outside of the can body at diametrically opposite points, said lugs being undercut on their inner faces so that their extremities may overlie the bead when the lid is placed upon the body and rotated to locking position, the inner extremities of the lugs being at a distance less than the long axis of the elliptical lid but greater than its short axis.
